(57) **CLAIM**

I claim ornamental design for a bolt carrier, as shown and described.

DESCRIPTION

FIG. 1 is a front perspective view of a bolt carrier showing my new design;

FIG. 2 is a rear, right side, perspective view thereof;

FIG. 3 is a rear, left side, perspective view thereof;

FIG. 4 is a right-side view thereof;

FIG. 5 is a left-side view thereof;

FIG. 6 is a front view thereof;

FIG. 7 is a rear view thereof;

FIG. 8 is a top view thereof; and,

FIG. 9 is a bottom view thereof.

The broken line in the drawings depicts unclaimed portion of the bolt carrier only and forms no part of the claimed design.
